UNITED STATES PATENT OFFICE

JOSEPH L. PERLETH AND JOHN COVEN, OF DUBUQUE, IOWA

GARMENT-HANGER ATTACHMENT

Application filed April 5, 1928. Serial No. 267,658.

The present invention relates to improvements in attachments for garment hangers and has reference more particularly to a sign having suitable advertising matter printed or otherwise arranged thereon and being attached to the garment hanger in such a manner as to render the sign conspicuous when hanging a garment on the hanger or removing a garment therefrom.

10 A further object of the invention is to provide a garment hanger attachment of the above mentioned character that can be readily and easily attached to the hanger without necessitating any alteration of parts of the hanger with which the sign is associated.

15 Still another object of the invention is to provide a garment hanger attachment of the above mentioned character which is simple in construction, inexpensive, strong and durable, and further well adapted to the purpose 20 for which it is designed.

Other objects of the invention will become apparent as the description of the invention proceeds and when taken in connection with the accompanying drawing.

25 In the accompanying drawing, forming a part of this application and in which like numerals designate like parts throughout the several views:

30 Figure 1 is a perspective view of one form of the sign, showing the manner in which the same is attached on a garment hanger that is formed of wire.

Figure 2 is a side elevation thereof, and

35 Figure 3 is a view similar to Figure 1, showing another form of the sign and its mode of attachment to the wire garment hanger.

40 In the drawing, wherein for the purpose of illustration is shown the preferred embodiment of our invention, the numeral 1 designates generally a wire garment hanger of the conventional construction which is formed at the top with an upwardly extending shank 45 portion 2, that terminates in a hook 3 for supporting the hanger from any suitable support.

The sign comprises a single blank of material such as metal or fiber, and this sign 4 may 50 have any suitable advertisement or indicat-

ing indicia printed or otherwise arranged on the side thereof. The sign is cut out to conform to the shape of the upper portion of the wire garment hanger, so that the upper edge of the sign will fit against the bottom edge of the upper portion of the wire garment hanger and for the purpose of securing the sign rigidly on the garment hanger so as to form a part thereof, the sign is formed at its respective ends with the oppositely disposed tongues or lips 5, that are bent over the sides 55 of the wire garment hanger.

A tongue 6 extends upwardly from the upper edge of the intermediate portion of the sign and the side edges of the tongue are curved in opposite directions to form a pair of lips 7 and 8 respectively which are bent around the adjacent portion of the shank 2 of the garment hanger for rest on the upper edge of the top portion of said garment hanger as clearly disclosed in Figures 1 and 2.

In Figure 3 of the drawing, there is shown a modification of the sign, wherein a pair of the tongues 9 and 10 respectively extend upwardly from the upper edge of the intermediate portion of the sign and are disposed in spaced relation with respect to each other and the free ends of these tongues are bent over the upper portion 11 of the wire garment hanger in opposite directions. The ends of the sign 12 shown in Figure 3 are formed with the tongues or lips 13 that are bent over the respective sides of the garment hanger in a manner similar to which the tongues or lips 5 of the sign 4 engage with the respective sides of the wire garment hanger.

When the sign is attached to the garment hanger in the manner as shown and described, the same will, at all times be visible, so that when a person is applying a garment on a hanger or removing a garment therefrom, the sign will attract attention. The simplicity of our attachment enables the same to be manufactured at a very low cost and readily and easily attached on garment hangers of the conventional construction without necessitating any alterations of the parts of the garment hanger with which said sign is associated.

While we have shown the preferred em- 100

bodiment of our invention, it is to be understood that minor changes in the size, shape and arrangement of parts may be resorted to, without departing from the spirit of the invention and the scope of the appended 5 claims.

Having thus described our invention, what we claim as new is:

1. In combination, a conventional garment hanger including a pair of arms forming a 10 substantial arc, a sign cut to conform to the shape of the arc, the upper edge of the sign fitting against the arc portion of the hanger, and tongues formed on the edge of the sign and bent over the adjacent portions of the 15 garment hanger to secure the sign in position.
2. In a garment hanger attachment, a sign, means for securing the same at its ends to the respective sides of the hanger, an additional 20 means at the top of the sign for securing the same to the adjacent portion of the hanger, said last mentioned means comprising a tongue extending upwardly from the upper edge of the intermediate portion of the sign, the side portions of the tongue being bent 25 back in opposite directions for engagement with the supporting hook associated with the garment hanger.
3. In combination, a conventional garment 30 hanger including a pair of interconnected arms forming a substantial arc, and a supporting hook extending upwardly from the arc portion of the interconnected ends of the arms, a sign cut to conform to the shape of the arc, tongues extending from the side 35 edges of the sign and being bent over the respective arms of the garment hanger, and additional tongues arranged on the upper edge of the central portion of the sign and being bent about the lower end portion of the supporting hook to secure the sign in a rigid 40 manner within the arc portion of the garment hanger.

In testimony whereof we affix our signatures.

JOSEPH L. PERLETH.
JOHN COVEN.
